UNITED STATES PATENT OFFICE.

ROBERT J. HAGERTY, OF PHILADELPHIA, PENNSYLVANIA, ASSIGNOR OF ONE-HALF TO FRANK H. HEBRON AND ONE-HALF TO THOMAS C. KELLY, BOTH OF PHILADELPHIA, PENNSYLVANIA.

NURSING BOTTLE.

Application filed December 23, 1921. Serial No. 524,352.

To all whom it may concern:

Be it known that I, ROBERT J. HAGERTY, a citizen of the United States, residing at the city of Philadelphia, county of Philadelphia, and State of Pennsylvania, have invented a certain new and useful Improvement in Nursing Bottles, of which the following is a specification.

The present invention has relation to the type of nursing bottle described in my co-pending application for patent as filed April 27, 1921 and serially numbered 464,830 and has for its leading object to improve and better the construction thereof in order to provide a more efficient and commercially useful article. A further object resides in the provision of general arrangements, connections and combinations of parts for attaining the results set forth in the foregoing object.

The invention consists of the improvements hereinafter described and finally claimed.

The nature, characteristic features and scope of the invention will be more fully understood from the following description taken in connection with the accompanying drawings forming part hereof, and in which—

Fig. 1, is a view in elevation, partly sectioned, of a nursing bottle embodying features of the invention.

Fig. 2, is a top or plan view of Fig. 1.

Fig. 3, is a view in elevation, upon a reduced scale, of the nipple closure and its lock-ring disengaged from a nursing bottle, and

Fig. 4, is a view in elevation, partly sectioned, of a nursing bottle embodying a slightly modified form.

For the purpose of illustrating my invention I have shown in the accompanying drawings two forms thereof which are at present preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the drawings and referring to Figs. 1 to 3, 10 designates the body of a nursing bottle, preferably formed of glass, which body terminates in a substantially conical neck 11 the mouth of which is provided with a bead to accommodate a nipple 13. Adjacent the juncture of said body and neck 11 the bottle is exteriorly screw-threaded as at 14 and the bottom of the bottle is provided with a similar screw-threaded portion 15 the uses for both of which will presently appear. Adapted to be detachably secured with respect to the nursing bottle is a nipple closure, cover or protector which is also preferably made of glass. It comprises an imperforate dome 16 terminating in a depending portion or skirt 17. The rim of the skirt is designated 19' to which is fitted the annular recessed portion 19 of a lock-ring 20. The ring is so positioned with respect to said bead that while it is secured thereto it is free to be rotated therearound. Thus in removing the nipple closure the two may be lifted from the bottle together. The lock-ring is interiorly provided with a screw-threaded portion for cooperatively engaging the screw-threads of the bottle and is provided with an annular flanged part 21 for bearing upon the rim 19' of the skirt 17. With nipple closure in proper position the rim 19' of skirt 17 is preferably free of the bottle neck so that the lock-ring when screwed to place clamps the parts as shown in Fig. 1. The juncture of the dome 16 and skirt 17 forms an internal shoulder 23 which abuts against that part of nipple 13 fitting over the bead of the bottle neck and forms an air-tight joint, since the nipple is of yielding material, as rubber, and it is possible to draw the shoulder 23 very tightly against said nipple. When the nipple closure is removed from the bottle neck it may, if desired, be secured to the bottle bottom by causing the lock-ring to engage screw-threads 15.

In Fig. 4, there is shown a bottle having a large mouth. Immediately above the screw-threaded portion of the body is an annular portion 24 of smaller diameter than the bottle body. The portion 24 is provided with a bead 25 to receive the nipple. 26 designates an inverted cup-shaped nipple-closure the lower part of which is adapted

to clamp the nipple between it and part 24 of the bottle when the lock-ring is secured to place.

Among the advantages claimed for the 5 above described nursing bottle mention may be made of the following:—

(a) A hermetical sealing of the bottle contents is secured thereby maintaining the same free from the attack of germs and 10 other exterior matter, flies, insects and the like.

(b) A closure is provided which positively prevents leakage of the bottle contents.

(c) Means is provided the bottle by which the nipple-closure may be attached to the bottle bottom whilst the bottle is being filled or otherwise used.

(d) The lock-ring is part of the nipple-20 closure so that the two may be removed together.

It will now be apparent that I have devised a novel and useful construction which embodies the features of advantage enumerated as desirable in the statement of the invention and the above description and while I have in the present instance shown and described the preferred embodiment thereof which has been found in practice 25 to give satisfactory and reliable results, it is to be understood that the same is susceptible of modification in various particulars without departing from the spirit or scope of the invention or sacrificing any of its 30 advantages.

What I claim is:

1. In an article of the character stated a bottle provided with an external screw-threaded portion that portion of the bottle 40 above said screw-threaded portion being of smaller diameter and provided with a bead, a nipple engaged over said bead, a nipple closure having an imperforate dome fitted over said nipple in impinging relation with 45 that part of the nipple engaging over said

bead and a lock-ring engaging the screw-threaded portion of said bottle for clamping said nipple closure upon said bottle.

2. A construction as described in claim 1, characterized by said lock-ring being secured to said nipple closure but free to be rotated with respect thereto.

3. A construction as described in claim 1, characterized by the bottom of said bottle being shaped and proportioned to removably accept said nipple closure and lock-ring.

4. In an article of the character stated a bottle the neck of which is provided with a bead, the juncture of the body and neck portion being exteriorly screw-threaded, a nipple engaging over said bead, a nipple closure having an imperforate dome terminating in a skirt and having an internal shoulder intermediate said dome and skirt, 60 and a lock-ring cooperatively engaging said skirt and screw-threaded portion for causing said shoulder to abut against that part of the nipple engaging said bead with the rim of said skirt positioned above that part 65 of the bottle neck immediately above said screw-threaded part.

5. In an article of the character stated a bottle externally provided with means for cooperatively receiving a locking-device, 75 that portion of the bottle above said means being of smaller diameter and provided with a bead, a nipple engaged over said bead, a nipple closure having an imperforate dome fitted over said nipple in impinging relation with that part of the nipple engaging over said bead and a locking-device engaging said means whereby the nipple closure may be drawn toward the bottle to increase the impinging relation of said closure with 80 the nipple.

In testimony whereof, I have hereunto signed my name.

ROBERT J. HAGERTY.
